DINNER PLATE

Franz Wagner, Chicago, Ill., assignor to Easter-ling China Company, Chicago, Ill., a corporation of Illinois

Application October 31, 1951, Serial No. 17,197

Term of patent 3½ years

(Cl. D44—15)

To all whom it may concern:

Be it known that I, Franz Wagner, a citizen of the United States, residing at Chicago, county of Cook and State of Illinois, have invented a new, original and ornamental Design for a Dinner Plate, of which the following is a specification, reference being had to the accompanying drawing, forming a part hereof.

Fig. 1 is a top plan view of a dinner plate showing my new design; and

Fig. 2 is a partial elevational, partial sectional view thereof on line 2—2 of Fig. 1.

I claim:

The ornamental design for a dinner plate, as shown.

FRANZ WAGNER.
